ATTORNEY

UNITED STATES PATENT OFFICE.

JOSEPH M. WHITE, OF ST. JOHNSBURY, VERMONT.

EGG-CASE.

1,324,708.

Specification of Letters Patent.

Patented Dec. 9, 1919.

Application filed May 22, 1917. Serial No. 170,265.

To all whom it may concern:

Be it known that I, JOSEPH M. WHITE, a citizen of the United States, residing at St. Johnsbury, in the county of Caledonia and

5 State of Vermont, have invented new and useful Improvements in Egg-Cases, of which the following is a specification.

This invention is an improved case for use in shipping frangible articles such as eggs or 10 the like by parcel post, express or otherwise, one object of the invention being to provide an improved case of this kind which is made of a single piece of material; another object being to provide an improved case embodying 15 ventilating ducts in the bottom and which serve to resiliently support the filler and to absorb shocks; another object being to effect improvements in the construction of the filler.

20 With the above and other objects in view the invention consists in the construction, combination and arrangement of devices hereinafter described and claimed.

In the accompanying drawings:—

25 Figure 1 is a perspective view of an egg case constructed and arranged in accordance with my invention, showing the same partly open.

Fig. 2 is a longitudinal sectional view of 30 the same.

Fig. 3 is a transverse sectional view of the same.

Fig. 4 is a plan of the case, unfolded.

My improved egg case 1 is made from a 35 single rectangular piece of material, such as cardboard or the like and comprises a bottom 1, sides 2, 3, ends 4 and a cover 5 having sides 6, 7 and ends 8. The sides 2, 3 are folded from the bottom on the lines 9 and are 40 separated at their ends from the ends 4 by cuts 10. Tabs 11 are folded from the sides on the lines 12 and are formed with tongues 13, which when the casing is arranged for use are inserted downwardly in slits 14 with 45 which the ends are provided, the tabs being arranged on the outer sides of the ends as shown.

The flange 6 of the cover is integral with the side 3 and is folded therefrom on the line 50 15 and doubled by a strip 16 which is pasted on the outer side thereof and is formed with end tabs 17 which are pasted on the outer sides of the end flanges 8, the said flange 6 being also folded from the cover on the line 55 18. The flange 7 is folded from the cover on the line 19 and is provided with end tabs 20

which are pasted on the outer sides of the flanges 8, said flange 7 being also formed with headed tongues 21 which are inserted in slits 22 in the sides 2 to fasten the cover in 60 place.

The top and bottom of the case are each stamped with a longitudinal ridge 23 and with cross ridges 24 which are suitably spaced apart. These ridges are resilient and 65 those of the bottom serve to yieldably support the contents of the case above the bottom and to absorb shocks, and the ridges of the cover also serve to absorb shocks, as will be understood.

A filler 27 which has cells 28 for the reception of the eggs is placed in the case together with top and bottom boards 29, 30 which are preferably also made of paper or cardboard but which may be made of any suitable material, and are provided with side and end flanges as shown. Said side and end flanges of the top and bottom boards respectively bear against the cover and bottom of the case so that said boards also serve as shock absorbing elements to protect the contents of 70 the filler.

The filler comprises an intermediate longitudinal bar 30^a, sides 31, intermediate cross bars 32 and ends 33. The members of the 75 filler are also preferably made of cardboard. The intermediate bar 30 and intermediate cross bars 32 are doubled longitudinally so that each of said bars is provided with spaced walls. Said bars 30, 32 are arranged 80 in reversed relation and are provided each with a pair of spaced slots to receive the walls of the other and are also provided near their ends with slots to receive correspondingly slotted portions of the outer members 85 31, 33. Said outer members 31, 33 have correspondingly slotted interengaging portions, near their ends, as shown so that the various members of the filler are detachably connected together. By the provision of the longitudinally doubled intermediate longitudinal and cross bars or partitions of the filler the latter is greatly strengthened and moreover 90 each of said bars is formed with a pair of spaced walls so that they serve to absorb 95 shocks and to protect the eggs or other articles in the cells.

My improved egg case may be readily manufactured at slight cost, when unfolded occupies very little space so that the case 110 when unfolded and emptied may be cheaply transported and the case may be also readily

set up and arranged for use, is strong and durable, and serves to effectually protect the eggs or other articles shipped therein.

While I have herein shown and described 5 a preferred form of my invention, I would have it understood that changes may be made in the form, proportion and construction of the several parts without departing from the spirit of my invention as defined by the ap- 10 pended claim.

Having thus described my invention, I claim:—

An egg case formed from a single piece of material and comprising a bottom, sides and 15 ends, a cover having side and end flanges, the cover forming an integral part of one of the side walls of the case, and being longitudi-

nally doubled, the doubled portion being formed with end tabs secured to the outer side of the end flanges of the cover, the ends of the case having slits, said side members of the case being terminally formed with tabs adapted to enter said slits, the bottom and cover each having a longitudinal rib and transversely extending ribs, a filler including 20 a bottom and a top wall, the top wall having upwardly extended side and end flanges, the bottom wall having depending corresponding flanges, and said flanges bearing against the cover and bottom of the case beyond said 25 ribs.

In testimony whereof I affix my signature.

JOSEPH M. WHITE.
